TOBACCO SMOKE FILTER

Worth Wade, Rosemont, Pa., assignor to American Viscose Corporation, Philadelphia, Pa., a corporation of Delaware

Application February 23, 1954, Serial No. 411,698

10 Claims. (Cl. 131—10)

This invention relates in general to tobacco smoke filters and in particular to a cigarette having a smoke filter incorporated therein and includes correlated improvements in the process of making such filters and in the articles so produced.

Tobacco smoke is made up of a mixture of gaseous compounds and finely divided solids and comprises tar, phenol, acetic acid, acrolein, carbon dioxide, water vapor and solid dust particles derived from the disintegration of the tobacco and the paper. Most of the substances contained in tobacco smoke are in the vapor state and are not removed from the smoke by prior filters that depend entirely on physical structure for filtration efficiency. Moreover, in prior filters of wood fiber, rayon, cotton, cellulose sponge and the like, the particles of the smoke are largely deposited on the surface of the filter and soon clog up the surface and increase the draw required to pull smoke therethrough.

According to the present invention, there is provided a tobacco smoke filter in the form of a mass of organic plastic fibers carrying a substantially permanent electric charge, and preferably in the form of organic fiber electrets. The present filter is also characterized by the fact that the fibers which make up the filter mass are not of substantially uniform diameter but, on the contrary, comprise fibers whose diameters vary widely over a substantial range of between 10 microns to 0.25 micron, and each individual fiber varies in diameter along its length. In the manufacture of organic plastic fibers in the rayon industry, in which the plastic mass is extruded through a spinneret, the resulting filaments have substantially the same diameters throughout their lengths and the variation in the diameter between fibers is only a fraction of the total diameter of either of them. In contrast to these fibers, the present invention utilizes organic fibers in which the variation in the fiber diameter is more than twofold throughout the mass and each fiber tapers substantially at its ends. In a preferred embodiment, the filter comprises at least some fibers which are thermoplastic and the filter may be heat-treated to bond the thermoplastic fibers to each other or to the other fibers at their points of contact. The filter may comprise an unshaped mass of loose fibers or a shaped mass, the shape being preferably fixed by thermally bonding the thermoplastic fibers on the surface of the filter. It has been found that the variation in the fiber diameter causes the present filter to be effective in depth and not to produce the majority of the deposition at the initial exposed surface of the filter mass.

The variable diameter fibers employed in the tobacco smoke filter of the present invention may be produced according to the process disclosed in the copending application of Derek E. Till and Carl R. Smallman Serial No. 400,252 filed December 24, 1953, now Patent No. 2,810,426, in which an organic plastic material is sprayed from a solution or molten mass into the form of fibers, the spraying taking place in a charged field so that a charge is induced on the fibers during their

formation. It would appear that the fibers so produced actually form miniature fiber electrets but, in any case, the mass of fibers so produced is characterized by having a strong and substantially permanent electric charge. It is possible by this process to induce upon the fibers either a positive or negative charge but the efficiency of the filter as a tobacco smoke filter appears to be substantially independent of the nature of the charge. The reason for this appears to be that the tobacco smoke particles have a charge induced upon them as they pass through the filter which is opposite to the charge on the fibers and the particles are then caused to be attracted to the surface of the fibers.

The organic fiber electrets may be formed from natural or synthetic resins as a class, such as vinyl resins, acrylic resins, polyamide resins, polyethylene resins and the like and from organic fiber-forming cellulose derivatives as a class such, for example, as cellulose esters, cellulose ethers and cellulose ester-ethers and compatible mixtures of resins and cellulose derivatives.

The present filter may be formed in whole of the organic fiber electrets or of a mixture of such electret fibers with non-electret fibers such, for example, as natural or synthetic fibers of any kind. For example, there may be mixed with the charged fibers such natural cellulose fibers as are derived from wood, straw, sisal, hemp and the like, and regenerated cellulose fibers formed by extrusion of viscose, cuprammonia and solutions of cellulose in its solvents, also protein fibers formed from gelatin, casein, zein, and peanut proteins, and mixtures of such classes of fibers. The non-electret fibers may also comprise mineral fibers such as asbestos, glass and rock wool, but in this embodiment it is advisable that the filter mass be heat-treated to bond the thermoplastic organic fibers to the mineral fibers to prevent their escape in the smoke stream during use.

The tobacco smoke filter of the present invention may be used in any tobacco product such as cigarettes, cigars or in a holder for a cigarette or cigar or in a tobacco pipe stem or in so-called water pipe smoking apparatus. Also, the filter may be formed to fit into a refillable filter holder for use in any smoking article.

For a more complete understanding of the nature and objectives of the present invention, reference should be had to the accompanying drawing in which

Figure 1 is a perspective view of one embodiment of the tobacco smoke filter of the invention.

Figure 2 is a representation of a mass of random-sized fibers utilized in the filter of the invention.

Figure 3 is a perspective view illustrating one method of forming the filter shown in Figure 1.

Figure 4 is a perspective view of a second method of forming the filter illustrated in Figure 1.

Figure 5 is a perspective view of the second embodiment of the filter.

Figure 6 is a perspective view of a cigarette incorporating the filter in accordance with the present invention.

Referring to Figure 1, the present filter comprises, in its preferred embodiment, a shaped cylindrical mass 10 of organic fibers 11, carrying an electric charge, the fibers being preferably in random distribution and varying in diameter and length.

Referring to Figure 2, it will be noted that the fibers used in the filter are characterized by the fact that each fiber varies in diameter over a substantial range along its length and with respect to each other. In the same mass, some of the fibers such as 11a are of very large diameter while others such as 11b are of extremely fine diameter. It should also be noted that the individual fiber such as fiber 11c varies in diameter throughout its length and particularly that the ends of the fiber have a pronounced and elongated taper. Thus these fibers differ

in their non-uniformity of diameter and length from artificial fibers which are produced by extrusion from spinnerets.

The filter of the invention may be produced in a number of ways, for example by forming the variable-diameter fibers into a web 12 as shown in Figure 3 and rolling this web upon itself to form a cylindrical roll 13. To maintain the cylindrical shape, the roll 13 may be subjected to heat sufficient to cause a substantial number of the thermoplastic fibers, preferably those in the surface layers, to bond to each other at their points of contact. Alternatively, there may be applied to the surface of the roll a binder, such as a solution of a resin, cellulose derivative, glue, gelatin, casein, water-soluble cellulose ether or other plastic or adhesive material, to bond the surface fibers. Thereafter, the roll may be cut transversely into individual filter sections as desired.

In Figure 4, there is shown another method of forming the cylindrical shape filter mass in which a web 14 comprising the non-uniform diameter fibers is gathered upon itself by folding, rolling, or twisting to form a cylindrical mass 15 which is drawn through the central hole of a die 16 having a heating element such as the electric heating coil 20. In passing through the die, the fibrous mass is compacted and at least the surface fibers are heated sufficiently to cause them to fuse together at their points of contact which fixes the cylindrical shape. Thereafter, the cylindrical mass 15 may be cut transversely into filter sections.

Another method of fixing the shape is shown in Figure 5 in which a loose mass of fibers 21 carrying a charge is enclosed in a collar or cylindrical cover 17 formed of a sheet material such as paper, metal foil, cellophane and the like. In the production of the filter unit as illustrated in Figure 5, the assembled unit may be subjected to a suitable treatment such as heat treatment so as to bond together a substantial number of fibers at their points of contact and to bond the fibers on the peripheral surface to the collar thereby preventing displacement of the fibers from the collar. Replaceable filter units of this type may be utilized in holders for cigarettes and cigars, pipe stems and any other smoking article.

In Figure 6, there is shown the cigarette of the invention comprising a paper wrapper 18 closing the granulated tobacco 19 and having disposed at one end the filter unit 10 of this invention. The filter unit 10 may be a mass of fibers, or it may consist of a preformed body wherein the fibers are bonded together, or it may be a unit of the type illustrated in Figure 5, as described hereinbefore. In order to assure retention of the filter unit in the end portion of the cigarette, at least the filter end of the cigarette may be subjected to a suitable treatment such as a heat treatment so as to bond the surface fibers to the wrapper 18. Where the filter unit has not been previously processed to bond the fibers together, the heat treatment may be sufficient also to bond together a substantial number of fibers. The fibers are thereby bonded into a coherent porous mass and the mass bonded to the wrapper so as to securely fix the unit within the cigarette.

I claim:

1. A tobacco smoke filter formed of a mass of randomly arranged organic fibers each of which has more than a two-fold variation in diameter, terminates in elongated tapered ends and carries a substantial permanent electric charge.

2. A tobacco smoke filter as defined in claim 1 wherein the maximum diameter of the fibers is between 0.25 micron and 10 microns.

3. A tobacco smoke filter formed of a mass of randomly arranged thermoplastic fibers each of which has a maximum diameter between 0.25 micron and 10 microns, has more than a two-fold variation in diameter, terminates in elongated tapered ends and carries a substantially permanent electric charge, a substantial number of the fibers being bonded together at their points of contact.

4. As an article of manufacture, a tobacco smoke filter comprising a collar and a filter body within the collar formed of a mass of randomly arranged organic fibers each of which has a maximum diameter between 0.25 micron and 10 microns, has more than a two-fold variation in diameter, terminates in elongated tapered ends and carries a substantially permanent electric charge.

5. An article of manufacture as defined in claim 4 wherein the fibers are thermoplastic fibers and are bonded together at their points of contact.

6. An article of manufacture as defined in claim 4 wherein the fibers are thermoplastic fibers and the fibers in contact with the collar are bonded to the collar.

7. As an article of manufacture, a cigarette comprising a tobacco smoke filter formed of a mass of randomly arranged organic fibers each of which has a maximum diameter between 0.25 micron and 10 microns, has more than a two-fold variation in diameter, terminates in elongated tapered ends and carries a substantially permanent electric charge.

8. An article of manufacture as defined in claim 7 wherein the fibers are formed of a synthetic resin.

9. An article of manufacture as defined in claim 7 wherein the fibers are thermoplastic synthetic resin fibers and a substantial number of the fibers are bonded together at their points of contact.

10. As an article of manufacture, a cigarette having at one end a cylindrical smoke filter, said filter having an outer casing formed of a non-thermoplastic fiber and a smoke filter within said casing formed of a mass of randomly arranged organic fibers each of which has a maximum diameter between 0.25 micron and 10 microns, has more than a two-fold variation in diameter, terminates in elongated tapered ends and carries a substantially permanent electric charge, a substantial number of said fibers being bonded together at their points of contact and the fibers in contact with said casing being bonded thereto.
